(57) **CLAIM**

The ornamental design for a ball, as shown and described.

DESCRIPTION

FIG. 1 is a front view of the ball;

FIG. 2 is a perspective view of the ball;

FIG. 3 is a reduced scale top view of the ball;

FIG. 4 is a reduced scale rear view of the ball;

FIG. 5 is a reduced scale bottom view of the ball;

FIG. 6 is a reduced scale right-side view of the ball; and,

FIG. 7 is a reduced scale left-side view of the ball.

Shading lines have been included for illustrative purposes only, to indicate spherical surface contour, and form no part of the claimed design.
